ALKYLARYL SULFONATE-HYDROXYETHYL-CELLULOSE DETERGENT COMPOSITION

Leslie R. Bacon and Clifton E. Smith, Wyandotte,
and Thomas H. Vaughn, Grosse Ile, Mich., as-
signors to Wyandotte Chemicals Corporation,
Wyandotte, Mich., a corporation of Michigan

Application January 5, 1949, Serial No. 69,252

4 Claims. (Cl. 252—161)

1

The present invention relates to a detergent composition based on an alkylaryl sulfonate and a detergent promoter or accelerator addition thereto consisting of hydroxyethylcellulose. Hydroxyethylcellulose is alternatively known in chemical terminology as "glycol cellulose" or the "ethylene glycol ether of cellulose." We have discovered, that in order to obtain the desired detergency accelerating effect, that the water-soluble hydroxyethylcellulose should be present in the amount of 1-63% by weight and preferably, 5-57%.

The synthetic detergent employed conforms to the general type formula: $R-\phi-SO_3-Na$ where R is an alkyl group having 9-16 carbon atoms, derived from a petroleum hydrocarbon distillate boiling in the range of 150-300° C., and ϕ is an aromatic hydrocarbon group of the benzene family.

It has of course previously been known to add various water-soluble, thickening and dispersing agents to synthetic detergents. We have determined however, after careful and exhaustive investigation, that the action of these thickening and dispersing agents is extremely specific and selective. When such an agent will produce an increase in deterutive action with one particular synthetic detergent, it will oftentimes actually decrease the detergency of another. Various thickening and dispersing agents which have heretofore been added to synthetic detergents are glues, gums, starches, pectin, albumin, and cellulose ethers. Methyl cellulose, carboxymethylcellulose, hydroxyethylcellulose and hydroxypropylcellulose are examples of the latter. In the case of sulfonated synthetic detergents, such as employed in the composition of our invention, and particularly in the case of sodium kerylbenzene sulfonate,¹ starch, Irish moss, methyl cellulose and hydroxypropylcellulose, for example, either reduce the detergency, or at best, produce only a minor degree of detergency promotion. Carboxymethylcellulose on the other hand is an excellent detergency promoter of sodium kerylbenzene sulfonate, as described and covered in the co-pending application of applicants C. E. Smith and T. H. Vaughn, together with E. F. Hill, Serial

No. 677,034, filed June 15, 1946, now Patent No. 2,568,334, issued Sept. 18, 1951.

Previous efforts involving the use of hydroxyethylcellulose, have been directed toward the composition formulation in which a synthetic detergent such as a sodium alkyl sulfonate or an alkylphenol-ethylene oxide condensation product (cf. U. S. Patent No. 2,335,194), is present in a minor proportion, viz. 10-30% by weight, and the hydroxyethylcellulose is present in major proportion, viz. 70-90% by weight. Here again, the detergency promotion is only slight, on the order of 10-15% improvement, and ineffective for all practical purposes, particularly when it is desired to use the detergent composition in competition and substitution for soap in laundering cotton fabrics.

In brief, for practical laundry washing, a synthetic detergent composition must have deterutive properties equal to or better than that of soap, if it is to be a commercially acceptable product. The detergent properties (as measured by the carbon soil removal tests as hereinafter described in detail) of the synthetic detergent composition should be promoted or accelerated to at least 150% or more of standard in order to be commensurate with those of a high grade soap. On the other hand, and for less exacting washing operations, it is necessary even then to obtain an appreciable increase in detergency, such as a promotion to 130% of standard, if the added effort and expense of the promoting agent is to be justified.

We have discovered that the addition of 5-57% of hydroxyethylcellulose to the alkylaryl sulfonates of the general type formula hereinabove given, e. g. sodium kerylbenzene sulfonate, produces an increase in detergent properties to 150-190% of standard; and that the addition of 1-63% of hydroxyethylcellulose produces an increase to 130% or greater of standard.

The alkylaryl sulfonate ingredient of the composition of our invention, as previously indicated, is derived from the alkylation of an aromatic hydrocarbon of the benzene family, such as benzene, toluene, xylene. Such alkylation may be effected by the Friedel-Crafts condensation of a chlorinated petroleum hydrocarbon distillate having 9-16 carbon atoms boiling in the range of 150-300° C., with the benzenoid hydrocarbon;

¹ Sodium kerylbenzene sulfonate is an alkylaryl sulfonate derived from a petroleum hydrocarbon distillate boiling in the kerosene range and benzene.

or the direct condensation of an unsaturated petroleum hydrocarbon of 9-16 carbon atoms with benzene, or its homologues. The resultant alkyl-aryl hydrocarbon is then sulfonated to form alkyl-aryl sulfonic acids which are subsequently neutralized, such as by means of caustic soda, to form the water-soluble alkylaryl sulfonates. During such neutralization step, excess sulfuric acid present in the alkylaryl sulfonic acid mixture is neutralized to an inorganic salt, such as sodium sulfate. The latter is customarily, and in a commercial alkylaryl sulfonate detergent product, permitted to remain and in some instances might even be increased by external addition. A proportion of about 60% sodium sulfate is usually found to be present in commercially available alkylaryl sulfonate type of synthetic detergents. Whether pure (i. e. sulfate-free) alkylaryl sulfonate or the "built" (Na_2SO_4 -containing) type is employed, the improved results of the composition of our invention are equally well obtained. The terms "alkylaryl sulfonate" and "sodium kerylbenzene sulfonate" when generally or more broadly employed hereinafter, in both the description and claims, shall be regarded as including both the sulfate-free and sulfate-containing forms of this ingredient of our compositions. Specific identification will of course be made of the respective forms where conciseness or particularization so requires.

The other ingredient of the composition of our invention is hydroxyethylcellulose or ethylene glycol ether of cellulose. The number of ethylene glycol residue groups ($\text{CH}_2\text{OHCH}_2-\text{O}-$) per glucose unit of cellulose in such hydroxyethylcellulose is dependent on the alkalinity of the solution in which it is to be employed. Generally, the number of glycol residue groups varies inversely as the alkalinity of the aqueous solution in which the composition is to be used. Thus, in approximately neutral aqueous solution, the hydroxyethylcellulose should contain 2-3 glycol residue groups per glucose unit of cellulose; whereas in solutions of above 10 pH, 1-2 glycol residue groups per glucose unit of cellulose are sufficient.

Inasmuch as it is not presently possible to determine precisely by analytical methods the proportion of hydroxyethyl groups substituted per glucose unit of cellulose (otherwise referred to as "degree of substitution"), the specification herein of number of glycol residue groups per glucose unit of cellulose is given on the theoretically calculated basis.

The detergent properties heretofore referred to, and subsequently to be referred to in this description, were determined by the following test procedure:

SOIL REMOVAL TEST PROCEDURE

A standard soiled cotton fabric is first prepared as follows:

Fourteen pieces of a standard muslin ("Indian Head" muslin 53 x 47, 5.15 oz. per sq. yd. manufactured by Nashua Mfg. Co.) are defini-
shed or pre-treated in order to remove the sizing or finish and to shrink the material, by a treatment with caustic soda solution, followed by a wash with sodium stearate, which is then followed by a number of rinses with soft water. The water used in this operation is softened to below one grain CaCO_3 equivalent to a gallon. Following such pre-treating operation, the muslin is extracted for 5 minutes and tumbled to dryness in a commercial gas-heated laundry dryer. 75 100.

The defini-
shed standard muslin, cut in pieces measuring $10\frac{1}{2}'' \times 36''$ are placed in a Monel metal wash wheel containing an emulsion of colloidal carbon black and water-soluble mineral oil. After thorough impregnation of the standard muslin in the carbon black and oil emulsion, it is removed piece by piece and passed once without folding through a power-driven household type wringer to squeeze out any residual aqueous dispersion, the wringer pressure being so adjusted as to leave in the cloth an amount of standard oil solution equal to $120\% \pm 1\%$ of the dry weight of cloth. The standard soiled muslin or test cloth is then dried and cut into test pieces measuring $2\frac{1}{2}'' \times 3\frac{1}{2}''$. Before actual use of the so-prepared standard soiled cloth, it is given a final check by the following described carbon soil removal test in a standard detergent solution, and over a range of several solution concentrations.

To evaluate the soil removal characteristics of synthetic detergent compositions, 0.25% by weight solutions of the composition to be tested are prepared in distilled water and 100 ml. portions of such solution are added to each of 10 one-pint jars of a "Launder-O-Meter" (type 12Q-EF-SPA, manufactured by Atlas Electric Devices Company) standard laundry test machine.

15 Fifteen $\frac{1}{4}''$ diameter stainless steel balls are placed in each jar, after which two pieces of the previously prepared standard soiled cloth are added to each of nine jars. In the tenth jar are placed two pieces of unsoiled but pre-treated cloth and this latter jar serves as a blank for determining the turbidity of the detergent solution. The so-prepared jars, heated to a temperature of $140^\circ \pm 2^\circ$ F. in a constant temperature bath are then placed in the "Launder-O-Meter" and run for 10 minutes at a speed of 42 ± 1 R. P. M. The jars are then removed from the test machine and replaced in the constant temperature bath. The contents of each jar to which the standard soiled cloth has been added are poured through a coarse screen to separate the steel balls and the standard soiled cloth from the soil suspension which is collected in a large beaker. The composite suspension thus attained is mixed thoroughly and a sample placed in a 10 mm. light absorption cell. The light absorption of this composite solution, as well as the light absorption of the solution in the tenth or "blank" jar containing the unsoiled cloth test pieces is then measured (by a "Fisher Electrophotometer"). By means of a calibration curve for the "Fisher Electrophotometer," such curve being constructed by obtaining light absorption values of known quantities of carbon black dispersion added to distilled water, the carbon soil removal value sought (in mg. of carbon per liter of solution) is obtained by taking the difference between the converted values of the light absorption of the composite solution or suspension from the nine jars and of the light absorption of the suspension in the blank jar.

60 The soil removal values are then reported as a percentage of that of a standard detergent solution used as a reference or control material; viz: by dividing the mg. of carbon removal value of the test material composition by the mg. of carbon removal value for the standard or control detergent solution which is determined concurrently in the same test run and on the same standard soiled test cloth, and multiplying by

As mentioned at the outset of this description, it was found that the detergency promoting action of hydroxyethylcellulose was extremely unpredictable, when applied to varying types of detergent compounds. The following Table I sets forth the results which were obtained by the above described carbon soil removal test procedure when applied to several different types of synthetic detergents or surface active agents, and also high grade (or high titer) soap, in the proportion of 10 parts of hydroxyethylcellulose per 100 parts of detergent. These tests were conducted in distilled water at 140° F. and at a uniform detergent concentration of 0.25%. In each case, the increase in carbon soil removal value is given as the per cent increase over the corresponding value of the particular detergent with no hydroxyethylcellulose present.

Table I

Detergent	Trade Name	Increase in Carbon Soil Removal Value by Addition of 10 parts of Hydroxyethylcellulose per 100 parts of Detergent	Percent
Ethylene oxide-hexitol condensation product.	"Tween 80"-----		7
Soap (41° titer)-----	"Armour's Flint Soap"-----		22
Fatty acid ester of colamino formylmethyl pyridinium chloride.	"Emulsept"-----		27
Sodium kerylbenzene sulfonate.	"Wyandotte Kreelon."		64

It will be noted from the foregoing table, that in the case of the several distinct types of surface active agents or detergents, namely non-ionic, sodium soap and quaternary ammonium compounds, that only a slight promoting or boosting effect was obtained. On the other hand, in the case of the alkyl-aryl sulfonate type of detergent, namely the sodium kerylbenzene sulfonate, a highly effective increase in detergency of 64%, was obtained.

The unique and unexpected ability of hydroxyethylcellulose to promote the detergent properties of sodium kerylbenzene sulfonate is further emphasized by the following test results where various other cellulose ethers and thickening agents were combined with sodium kerylbenzene sulfonate. These results are given in the following Table II. These tests were similarly conducted in distilled water at 140° F., at a uniform sodium kerylbenzene sulfonate concentration of 0.25%. The detergency values are given in "per cent of standard," the standard of course being the sodium kerylbenzene sulfonate alone with no additive agent present.

Table II

Sodium Kerylbenzene Sulfonate (parts by weight)	Additive Agent (parts by weight)	Detergency (percent of Standard)
100-----	Starch Carboxymethylated-10 ("Starch R-9")-----	100
100-----	Irish Moss ("Carragar")-10-----	97
100-----	Methylcellulose-10-----	88
100-----	Hydroxypropylcellulose-10-----	129
100-----	Hydroxyethylcellulose-10-----	164
100-----	Hydroxyethylcellulose-40-----	189

The above results not only substantiate the outstanding detergency promoting powers of hydroxyethylcellulose, but they also are of a sur-

prising nature in that they reveal a very closely homologous cellulose ether, namely hydroxypropylcellulose, to be of relatively low detergency promoting ability for sodium kerylbenzene sulfonate.

The efficacy of the addition of 10 and 40 parts, respectively, of hydroxyethylcellulose per 100 parts of sodium kerylbenzene sulfonate next led to the examination of the detergent action of the complete two component system: sodium kerylbenzene sulfonate-hydroxyethylcellulose. As a result of this latter investigation, it was discovered that there is a well defined zone of the proportions of these two components, where the desired, and outstanding promotion of detergent properties are obtained. This statement is further illustrated by the curve shown in the drawing.

As noted by the title legend to this drawing, 20 it is a curve showing the relationship of the carbon soil removal values in the two component system (sodium kerylbenzene sulfonate-hydroxyethylcellulose) over the range proportions of ingredients varying from 0 to 100% sodium kerylbenzene sulfonate, and conversely from 100 to 0% hydroxyethylcellulose. Test formulation mixtures of these two ingredients over such range proportions, were made up and tested for their detergent properties, according to the carbon soil removal test procedure hereinbefore described. These tests were conducted in distilled water at 140° F. with a total concentration of ingredients equal to 0.25%. The curve shown in the drawing represents the "per cent of standard" soil removal values that were obtained over the 0 to 100% range proportions of the two ingredients. The standard, or 100% value was of course the carbon soil removal value for the composition consisting entirely of sodium kerylbenzene sulfonate alone with no hydroxyethylcellulose present.

As in previously described test results of compositions embodying the principle of our invention, the precise identification of the ingredients are as follows:

Sodium kerylbenzene sulfonate:

"Wyandotte Kreelon 4D" Lot No. C-2687 M, manufactured by Wyandotte Chemicals Corporation, containing 58% Na₂SO₄.

Hydroxyethylcellulose:

"Cellosize-WS," manufactured by Carbide & Carbon Chemical Corporation, having a viscosity of 87 cps. and over 2 degrees of substitution of ethylene glycol groups per glucose unit of cellulose.

From the results shown in the drawing, it will be seen that as low as 1% hydroxyethylcellulose effects a detergency increase to 130% of standard. This 130% of standard detergency increase is maintained up to the proportion of 37% sodium kerylbenzene sulfonate and 63% hydroxyethylcellulose. Hence the area bounded by the 130% standard soil removal line and the portion of the curve above it, is denoted as "zone of 30% promotion." Thus the combination of 1-63% of hydroxyethylcellulose with sodium kerylbenzene sulfonate, produces 130% or greater of standard detergent value.

Similarly, from Fig. 1, it will be noted the "zone of 50% promotion" is bounded by the vertical ordinates corresponding to 5-57% of hydroxyethylcellulose and the 150% of standard soil removal value by the horizontal ordinate. This means that a formulation containing

43-95% sodium kerylbenzene sulfonate and 5-57% hydroxyethylcellulose possesses a carbon soil removal value of 150% of standard or greater. And as previously pointed out in the specification, this value of 150% of standard is equal to or better than that of high grade soap in the washing of cotton fabrics.

We have also discovered that hydroxyethylcellulose when combined with sodium carboxymethylcellulose will give an equally efficacious detergency promotion of sodium kerylbenzene sulfonate. Thus, a mixture containing equal parts of hydroxyethylcellulose and sodium carboxymethylcellulose was mixed in the ratio of 10 parts by weight with 100 parts of sodium kerylbenzene sulfonate (58% Na_2SO_4). On making this composition up into a solution in distilled water of 0.25% by weight of concentration on the basis of sodium kerylbenzene sulfonate present, a carbon soil removal of 174% of standard was obtained. This compared with values of 164% of standard where hydroxyethylcellulose alone was used and 159% of standard where sodium carboxymethylcellulose was used (10 parts of cellulose ether per 100 parts of sodium kerylbenzene sulfonate in each case). It will thus be seen that this mixture of equal parts of these two particular cellulose ethers resulted in a synergistic effect inasmuch as the detergency, or carbon soil removal value was greater than the highest value that could be obtained from equivalent amounts of either one of them.

The compositions of our invention also embrace the alkaline salt "built type" wherein such inorganic salts or "builders" as the sodium carbonates; sodium carbonate, sodium bicarbonate, modified soda (a combination of the first two); the sodium phosphates (ortho-, meta-, pyro-, and tripolyphosphates, and including those polyphosphates of the calcium- and magnesium ion sequestering type whose $\text{Na}_2\text{O}/\text{P}_2\text{O}_5$ ratio ranges from 1:1 to 1 $\frac{1}{3}$:1); sodium silicates (meta-, ortho-silicates and water glasses) and sodium borates (borax and meta-borate) are added. Such additions of inorganic alkaline salts are made in proportions of up to 65% by weight of the total composition.

Thus, the "promoted" and "built" formulations of our invention have the following range proportions of ingredients:

	Per cent
Sodium alkylaryl sulfonate	25-90
Hydroxyethylcellulose	1-63
Inorganic alkaline salt	1-65

In the above formulations, where the inorganic alkaline salt or "builder" imparts an alkalinity of above 10 pH to the aqueous washing solution, the hydroxyethylcellulose, as hereinabove mentioned, may have a degree of substitution of 1-2 glycol residue groups per glucose unit of cellulose.

The relatively high proportion of alkaline salt building that is tolerated by such formulations is illustrated by the following tabulated results, where the amount of builder was present in amounts up to, and approaching the 65% maxi-

mum limit, while even then a 30% or greater detergency improvement was obtained:

5	Ingredients—Per Cent by weight				Detergency Per Cent of Standard
	Na Kerylbenzene Sulfonate	Hydroxyethyl Cellulose	Sodium Carbonate	Modified Soda	
10	100	—	—	—	100
25	25	10	65	—	136
30	30	10	60	—	140
35	35	5	60	—	136
40	40	10	50	—	142
15	25	10	—	65	134
30	30	10	—	60	137
35	35	—	—	60	135
	40	10	—	50	137

Other modes of applying the principle of our invention, in addition to the one hereinabove described and illustrated in detail, may be employed, 20 provided the elements stated by any of the following claims or the equivalent of such elements be utilized.

We, therefore, particularly point out and distinctly claim as our invention and discovery:

- 25 1. A synthetic detergent composition consisting essentially of sodium alkylbenzenesulfonate, whose alkyl group contains 9-16 carbon atoms and 1-63% by weight of hydroxyethylcellulose.
- 30 2. The composition as in claim 1, but wherein the hydroxyethylcellulose is present in the amount of 5-57% by weight.
- 35 3. The composition as in claim 2 where the hydroxyethylcellulose contains 2-3 glycol residues per glucose unit of cellulose.
- 40 4. The composition as in claim 1, but wherein there is added up to 65% by weight of the total resultant composition of an inorganic alkaline salt builder selected from the group consisting of sodium carbonate, sodium bicarbonate, modified soda, sodium ortho-, meta-, pyro-, tripoly-phosphates, sodium phosphates of the calcium- and magnesium ion sequestering type having an $\text{Na}_2\text{O}/\text{P}_2\text{O}_5$ ratio in the range of 1:1 to 1 $\frac{1}{3}$:1, sodium meta-, ortho-silicates, water glass, borax and sodium borate.
